UNITED STATES PATENT OFFICE.

THADDEUS FAIRBANKS, OF ST. JOHNSBURY, VERMONT.

RADIATOR.

SPECIFICATION forming part of Letters Patent No. 231,413, dated August 24, 1880.

Application filed January 6, 1880.

To all whom it may concern:

Be it known that I, THADDEUS FAIRBANKS, of St. Johnsbury, Caledonia county, in the State of Vermont, have invented certain new and 5 useful Improvements relating to Warming the Air of Rooms; and I do hereby declare that the following is a full and exact description thereof.

I attain the moderate temperature of the 10 final radiating-surfaces and the uniformity of temperature and other advantages due to hot-water heating with the power of automatic control of the fire and active circulation of the heat horizontally to distant portions of an ex- 15 tended building or to a separate building due to steam-heating. I combine a hot-water system of pipes or radiating apparatus with a steam-generating system at the furnace, using pipes and suitable provisions for connecting 20 to carry the steam to the hot-water system, to impart the heat from the steam to the water, and to conduct away the resulting water of condensation.

The accompanying drawing forms a part of 25 this specification, and is a side elevation of my apparatus, partly in section, with a section of a part of the building in which it is used.

A is the floor, and A' is one of the walls of 30 a building or of an apartment thereof. I will designate the space to be warmed, briefly, as a "room."

B is a steam-pipe, bringing steam at any 35 convenient pressure from a distant boiler, M. It extends up to a considerable height, then horizontally a little, and thence downward into my hot-water-heating system. It is continued downward through the hot-water-heating apparatus by a larger pipe, (marked B'), which I will term a "heating-vessel." Near 40 the bottom it again contracts, and emerges at the base of the same size as it enters. It extends from the base back again to the boiler M.

The hot-water apparatus is composed of 45 several parts suitably disposed to present the water efficiently to the steam-pipe B' and receive heat therefrom, and allow the water thence to circulate through the other bends and parts and give off its heat to the air of the 50 room.

D' is a continuous upright part of the hot-

water apparatus, which I will term a "heating-chamber," surrounding the steam-pipe B'. D² is a horizontal part extending from the top of D'. The water heated by the steam-pipe B' rises in D', flows horizontally through D², descends through D³, flows along through D⁴, descends through D⁵, flows horizontally through D⁶, descends through D⁷, and finally flows horizontally through D⁸ and succeeding 55 similar connections to the base of D', in which it again rises. Its circulation through D², &c., gives heat to the air of the room and cools the water, but each rise through D' again heats it.

The pipes D' D² D³, &c., are formed and ar- 60 ranged to allow an active circulation of the air of the room to the outer surfaces thereof.

The portions D³ and D⁷, being in line with each other, are made in one, with simply a 65 tight partition across at the mid-height. 70

Modifications may be made in the details 75 without departing from the principle or sacrificing the advantages of the invention. There may be more of the hot-water apparatus. The returns may be nearer together or wider apart. They may extend up and down or inclined. I can use a coil in place of the large straight pipe B', in which the steam imparts 80 its heat to the water.

I esteem it important to provide for a reasonable amount of expansion and contraction 85 of the water relative to the containing vessels or pipes. For this I provide a globe, E, to contain air, which may, by its elasticity, be compressed or expanded within wide limits. Ordinary provisions (not shown) may be made 90 for adding water and for draining the apparatus when desired.

I propose to use the device for warming all 95 kinds of buildings and apartments. I esteem it especially adapted for green-houses. The temperature may be controlled by a cock on the steam-pipe B, (not shown,) or by a cock or other device for checking the circulation, (indicated by a circle at G in the figure.) The 100 partial closing of such cock, and thus retarding the flow of the water, allows the water in the immediate vicinity of the steam-pipe B² to become heated up to the temperature of the steam without much raising the temperature of the other parts of the radiator, while a slight increase in the opening will allow a slow cir-

culation and allow the effect to be graduated with great nicety.

I am aware that steam led through pipes plain and variously coiled and convoluted has 5 been employed to heat water and other fluids, eminently sugar-liquor. Such, broadly, is not sought to be covered in this application.

I claim as my invention—

The combination of the radiator having tortuous passages connected with a heating-

chamber, D', with the contained heating- vessel B' and steam-supply B, as and for the purposes herein set forth.

In testimony whereof I have hereunto set my hand this 22d day of December, 1879, in 15 the presence of two subscribing witnesses.

THADDEUS FAIRBANKS. [L. S.]
